UNITED STATES PATENT OFFICE.

COLIN MCINTOSH, OF TACOMA, WASHINGTON.

DESIGN FOR A KEY-TAG.

SPECIFICATION forming part of Design No. 21,338, dated February 9, 1892.

Application filed December 28, 1891. Serial No. 416,378. Term of patent 7 years.

To all whom it may concern:

Be it known that I, COLIN MCINTOSH, a citizen of the United States, and a resident of Tacoma, in the county of Pierce and State of Washington, have invented certain new and useful Improvements in Designs for Key-Tags; and I do declare the following to be a full, clear, and exact description of the invention, such as will enable others skilled in the art to 5
10 which it appertains to make and use the same, reference being had to the accompanying drawings, and to letters of reference marked thereon, which form a part of this specification.

Figure 1 of the drawings is a face view of 15 one side of the tag, and Fig. 2 is a similar view of the reverse side.

This invention has relation to certain new and useful designs in key-tags; and it consists in the novel form and configuration there- 20 of, as shown and hereinafter described.

The letter A designates the tag, of circular disk form, with parallel faces, on which are marked a series of circular concentric lines a. These circular concentric lines are shown as 25 intersected at intervals by a series of radially-disposed lines b, which, however, do not enter within the inner circle. These radial lines subdivide the circular spaces formed by the outer series of the concentric lines. The re- 30 verse face of the disk is also shown as divided

by concentric circular lines c and intersected by radial lines d, the latter, however, being shown as alternately broken. The obverse face is shown in Fig. 1, the characteristic feature being the concentric circular lines intersected by the radial lines. The reverse face is shown in Fig. 2, the characteristic feature being the concentric circular lines intersected by the alternately broken radial lines. The arrangement of these lines may be varied in 35 minor particulars without changing the characteristic features of the design. 40

The lines may be formed either intaglio or relief without materially affecting the character of design. 45

What I claim is—

1. The design for a key-tag, substantially as herein shown and described.
2. In a design for key-tags, the design for the obverse face, substantially as herein shown 50 and described.
3. In a design for key-tags, the design for the reverse face, substantially as herein shown and described.

In testimony whereof I affix my signature in 55 presence of two witnesses.

COLIN MCINTOSH.
